UNITED STATES PATENT OFFICE.

PETER MEYER, OF COLOGNE-NIPPLES, AND KARL NUESE, OF ALTONA, GERMANY; SAID MEYER ASSIGNOR TO SAID NUESE.

TYPE-WRITING MACHINE.

1,030,005.

Specification of Letters Patent.

Patented June 18, 1912.

Application filed March 6, 1905. Serial No. 248,555.

To all whom it may concern:

Be it known that we, PETER MEYER, a subject of the King of Prussia, and resident of Nordstrasse 27, Cologne-Nippes, 5 Germany, and KARL NUESE, a subject of the King of Prussia, and resident of Lessingstrasse 22, Altona-on-the-Elbe, Germany, have invented certain new and useful Improvements in Type-Writing Machines; 10 and we do hereby declare the following to be a full, clear, and exact description of the invention, such as will enable others skilled in the art to which it appertains to make and use the same, reference being had to the 15 accompanying drawings, and to letters or figures of reference marked thereon, which form a part of this specification.

The subject of our invention is a type-writing machine which presents the hereinafter described differences and advantages as compared with the machines heretofore known.

In the accompanying drawings:—Figure 1 shows the machine in longitudinal section, 25 and Fig. 2 in plan; Fig. 3 shows in plan the device for setting the type-carrier. Fig. 4 is an underside view of the machine. Fig. 5 shows a type-carrier in plan, drawn full size, while Fig. 6 is a vertical section. 30 Fig. 7 shows the carriage-feed-mechanism in elevation, and Fig. 8 in plan. Fig. 9 is a front elevation showing the device for feeding the carriage backward, while Fig. 10 shows the said device in side elevation.

35 The key-levers 2, which are capable of turning about a common axis 1, are arranged in a known manner in two groups, of which those on the left-hand cause the type-carrier to turn to the left, and those 40 on the right-hand cause it to turn to the right (Fig. 4). This rotation is produced by means of the two bell-crank-levers 4, which are pivoted at 5 and of which the arms beneath the key-levers bear a cross-bar 45 6. In this cross-bar 6 are arranged adjustable screw-pins 7, the ends of which take the pressure of the key-levers 2 and transmit it to the bell-crank lever 4. Exact 50 regulation of the throw of the cross-bars and therefore also of the angle of oscillation of the segment can be obtained for each key-lever 2 by turning these screws to the right- or to the left-hand. The upwardly-extending arms of the bell-crank levers 4 each 55 engage in a slot 9 in the arms 11 mounted

on the hollow shaft 10 (Figs. 2, 3) and, as the keys are struck, produce rotation of the shaft 10 in one or the other direction. In the position of rest of the two levers 4, the fingers 12 of the arm 11 lie on the ends of 60 the levers 4, so that the hollow shaft 10 bearing the type-carrier is locked in the mid position. On the other hand, the bent finger 13 of one arm 11 locks the corresponding lever 4 and with it the corresponding group of key-levers, if the other arm 11 has been turned by the corresponding lever 4. The position of rest of the two arms is defined by stops 14.

The hollow shaft 10, which is capable of 70 turning about the vertical spindle 15, carries with it in its rotation the segmental type-carrier by means of an eccentric pin 16, which is secured thereto and bears a fork-shaped piece 16^a, (Figs. 1, 5, 6.) The type-carrier consists of three segmental frames 60, which are rotatably mounted on the upper end 25 of the shaft 15. The several types 61 are arranged at equal distances apart on the periphery of the segment- 80 pieces in such a manner that, when the type-hammer is thrown forward, only the type brought in position for the time being is caused to print. Each type 61 is acted upon by a spring 62 and is guided in the walls 85 of the segment-pieces in such a manner that turning or twisting of the types is impossible. This is effected by making the front part of the rod or shaft bearing the type of rectangular form, while the rear part of 90 the said rod or shaft is made round and is guided in a correspondingly-shaped guide in the rear wall of the segment-piece. As the type is thrown forward, the spring 62 arranged between the inner edge of the 95 outer wall of the segment-piece and the round part of the shaft or rod bearing the type, is compressed, so that it can return the type to its initial position after the blow has been struck.

100 The hollow shaft 10 is provided at its lower end with an arm 17, the forked end of which extends to the locking pins 18 (Figs. 1, 2 and 3.) These pins are arranged in the arc of a circle, and guided in holes in the 105 arc-shaped frame 19, and extend through the base-plate 20 to arms 21 extending from the key-levers 2, which arms hold the pins, when in the position of rest, at such a height that the ends of the arm 17 can go freely 110

past beneath the enlarged parts 22 of the pins 18, Fig. 1. If however one of the key-levers is depressed, the corresponding locking-pin 18 resting on the arm 21 follows it to such a distance that the enlarged part 22 thereof prevents further rotation of the arm 17 and shaft 10, Fig. 3, and by this means the type in the type-carrier corresponding to the key-lever depressed is brought accurately into the printing position. The locking pins 18 either rest, by reason of their weight, on the arms 21, or their lower ends are caused by small spiral springs 23 (Fig. 1) to follow with certainty the downward motion of the arms 21. The arrangement of the locking pins 18 above the base-plate 20 insures their being easily accessible and permits the shaft for turning the segment-parts to be made hollow so that the spindle 15 can be moved vertically in order to adjust the height of the segment-pieces. For this purpose, the spindle 15 is securely guided at the bottom in the base-plate 20 and at the top in a cross-piece 24 connected to the base-plate 20.

The adjustment of the height of the type-segments is effected in the following manner: The type-carrier-shaft 15, which is prevented from turning, is connected at its lower end to two levers 71 (Figs. 1 and 4) arranged beneath the base-plate 20, which levers are secured at their other ends to the ends of two hollow shafts 72 turned toward the center line of the machine, which hollow shafts are rotatably arranged on a shaft 73 mounted on the frame. The other ends of the hollow shafts are each connected to a key-lever 74, which levers move in guides 75 arranged on the underside of the base-plate 20. One of the two key-levers 74 effects the lifting of the type-carrier-shaft 15 in such a manner that the middle segment-piece is brought into the printing position, while the other key-lever 74 lifts the shaft 15 to such a height that the lower segment piece is brought into the printing position. In order to be able to regulate the travel of the two key-levers 74 and thereby to effect the correct adjustment of the two lower segment-pieces into the printing position, set-screws 76 are arranged at the lower ends of the guides 75, so that the corresponding key-lever can only be depressed until it strikes against the corresponding set-screw 76. For returning the type-carrier-shaft 15 to its position of rest, the spiral spring 84 acts on its lower end. Since the upper segment-piece is normally in the printing position, the writing can be very easily seen.

The segment-piece 60 for the meantime in the printing position is carried along by the rotation of the hollow shaft 10 during the depression of a key by the aid of the forked part 16^a, and the type corresponding to the

key is brought into the printing position. By dividing the type-carrier into three, it is possible that in all cases only that segment-piece shall be turned which is opposite to the limbs of the part 16^a. In order to prevent the other parts from being carried along therewith, they are locked by a pin 85 fastened to the cross-bar 24, which pin has a recess 86 at the height of the forked part 16^a (Figs. 1 and 6) so that only the segment-piece at the same height can be turned.

In order to enable each of the two lower segment-pieces 60 to be held in the printing position for a longer time, without it being necessary to keep one of the two key-levers 74 continuously depressed, a locking device is provided for each of the two key-levers. This locking device consists of a locking pin 78 (Fig. 1) which is movable in a guide 77 mounted on the base-plate 20 and which is adapted to engage in a recess 79 in the lever 71. The pin is acted upon by a spring 80, which tends to depress it, and bears at its upper end a head 81, which has a small pin 82 on its lower edge. This pin normally lies against the upper surface of the guide 77 and therefore holds the locking pin 78 out of engagement with the recess 79, which however during rotation of the head 81 can snap into a hole 83 in the guide 77 by the action of the spring 80, so that the locking pin 78 can engage with the recess 79 of the lever 71 and thus hold the key-lever 74 in its depressed position.

In order to feed the carriage, two transverse levers 44, 45 are arranged close beneath the key-levers 2 (Fig. 4) and extend over the whole width of the two groups of keys. The front lever 44 is moved by the left-hand group of key-levers and is capable of turning about its right-hand terminal point at 47. The rear lever 45 is moved by the right-hand group of key-levers and is capable of turning about the left-hand terminal point at 46. The levers 44, 45 are held up by springs 49 and are provided at their free ends with slots whereby they are guided on the pins of the standards 46 and 47. The two transverse levers 44, 45 thus move in opposite directions during the manipulation of the key-levers, and act on a short lever 42 which is likewise capable of turning about the axis 1. This lever 42 abuts against a stop 43 and engages with the undersides of the levers 44, 45 by means of an arm 42' (Figs. 1 and 4).

The lever 42 is connected by means of a rod 41 with the lever 32, which is pivoted at 31 and bears a locking pawl 30 for engaging with the teeth of the ratchet wheel 39 (Fig. 7). By pressing on any one of the key-levers 2, the lever 32 is accordingly turned against the action of the spring 40 in the direction of the arrow and this rotation does

not take place until the type-carrier has been set by the corresponding key. The turning of the lever 32 with the locking pawl 30 thus has for its result that the locking pawl acts on the lever 34 (which is capable of turning about the axis 33) in the opposite direction to that in which the said lever is moved by its controlling spring 35, whereby the locking lever 37 (which is capable of turning about the axis 36 and which engages with a slot in the locking pin 26 for locking the segment-pieces 60 in the printing position) is released by the pin 38 of the lever 34. By this means, the pin 26, under the action of the spring 28, can rise and effect the locking of the type-carrier by entering a hole, corresponding to the type selected, in the arc-shaped piece 29 secured to the hollow shaft 10. If now, on releasing the key-lever, the ratchet-wheel 39 is released by the locking pawl 30, so that it can turn through one tooth or step and effect the feed of the carriage, the tooth of the wheel 39 lying within reach of the lever 37 acts on the lever 37, so that the latter draws the locking pin 26 down again and is finally held in its position again by the pin 38 of the lever 34. Since both levers 44, 45 are provided with adjusting screws 48, the action of all the key-levers can be regulated so that the locking thereof only takes place after the type-carrier has been set. The driving of the hammer 51 (Fig. 1) which produces the blow struck by the type, is effected from the carriage-feed mechanism by means which do not form part of the present invention.

In order to render it possible to write on one and the same machine with two or more different sizes of space between the characters, it is necessary to provide both the racks of the carriage, and also the corresponding wheels of the carriage-feed-mechanism, with teeth of two or more different pitches. According to which size of space between characters is desired, one of the toothed wheels mounted on the sleeve of the driving shaft is coupled to the said sleeve whereby a longer or shorter distance of feed of the carriage is obtained. The coupling of the toothed wheels mounted on the sleeve is effected by the movement of a feather 52 (Fig. 8) which can be moved in a longitudinal groove in the sleeve by means of the screw nut 53, so that the front end 52' of the feather couples either one or other of the two toothed wheels 50, 50' with the sleeve. The two latter wheels have teeth of different pitch, so that, each time a key is struck, the carriage is fed through a different distance, accordingly as one or other wheel is coupled to the sleeve.

In order to obtain a rapid and certain setting of the carriage or slide to any desired point in the rearward direction, the

arrangement hereinafter described is employed: This arrangement consists of a feed-lever 114 (Figs. 9 and 10) which is pivoted at 115 and is provided at one end with a feed-pawl 116 which engages with the teeth of one of the carriage-feed-wheels 50, 50'. At the other end, the lever is connected to the key-lever 118, which is pivoted at 119 to the base-plate 20. A standard 120, which at the same time forms a guide for the lever 114, contains a spring 121 which always tends to hold the feed-pawl out of engagement with the feed-wheel 50 or 50'. By depressing the key-lever 118, the pawl comes into engagement with the feed-wheel 80 and effects the backward movement of the carriage. By means of an elongated aperture or slot 122 formed in the key-lever 118, the throw of the key-lever, and thus also the distance through which the carriage is fed backward, is limited. According to the size of the said slot, the carriage can be moved back through a distance corresponding to the width of, for example, one, two, or more types.

What we claim as our invention and desire to secure by Letters Patent is:

1. In a typewriter, the combination of two groups of pivoted key-levers, two bell-crank levers one pivoted below each key-lever group and operated by the key-levers thereof but not by the levers of the other group, a type-carrier shaft, a type-carrier mounted thereon, a hollow shaft containing the said shaft and rocked in opposite directions by the two bell-crank levers, and means for transmitting the vibratory motion of the hollow shaft to the type-carrier, substantially as described.

2. In a typewriter, the combination of two groups of pivoted parallel single-armed key-levers, two independent bell-crank levers one pivoted below each key-lever group and each presenting a cross-bar located obliquely to the key-levers of the group and possessing adjustable stops one below each such key-lever and depressed by it on its actuation, a type-carrier shaft, a type-carrier mounted thereon, and means for transmitting the motion of the bell-crank levers 110 to the type-carrier, substantially as described.

3. In a type-writer, the combination of a type-carrier shaft, a plurality of segmental type-carriers loosely mounted on said shaft, a hollow shaft surrounding the carrier shaft, a forked member connected to said hollow shaft adapted to rotate one of the type-carriers, and means for locking the remaining carrier.

4. In a typewriter, the combination of a type-carrier, a hollow shaft, means for connecting the said carrier with the shaft, a perforated sector rigidly connected with the latter, a spring-actuated locking-pin for 130

engaging the holes in the sector, carriage feed-mechanism comprising a ratchet-wheel and a locking-pawl, and means for connecting said locking-pin and pawl, substantially as described.

5. In a typewriter, the combination of a type-carrier shaft, a spindle, levers mounted thereon at their one end and connected at their other end to the bottom of said shaft, 10 key-levers operating said spindle-levers, and means for locking the spindle-levers in any desired position, substantially as described.

6. In a typewriter, the combination of a type-carrier shaft, a spindle, notched levers mounted thereon at their one end and connected at their other end to the bottom of said shaft, key-levers operating said notched levers, and spring-actuated catches located on a stationary part above said notched levers and engaging in the same in the depressed position of the key-levers, substantially as described.

7. In a type-writer, the combination of two groups of pivoted parallel key-levers, 25 transverse levers arranged beneath said key-

levers and adapted to be moved in opposite directions thereby, a carriage, a central lever for feeding the carriage, and means connecting said central and transverse levers.

8. In a type-writer, the combination of a type-carrier, a hollow shaft, means for connecting said carrier and shaft, a perforated sector rigidly connected to said hollow shaft, a locking-pin adapted to engage said perforations, a spring acting on said locking-pin, carriage feed mechanism comprising a ratchet-wheel and a locking member, and means for connecting said locking-pin and locking-member.

In testimony that we claim the foregoing 40 as our invention, we have signed our names in presence of two subscribing witnesses.
